UNITED STATES PATENT OFFICE

OTTO CARLSON, OF JAMESTOWN, NEW YORK, ASSIGNOR TO JAMESTOWN METAL EQUIPMENT COMPANY, INC., OF JAMESTOWN, NEW YORK, A CORPORATION OF NEW YORK

RADIATOR

Application filed July 17, 1929. Serial No. 378,903.

This invention relates to an improvement in radiators for cooling the engines of automobiles, trucks, tractors and other motor vehicles, and more particularly to radiators of the cellular type in which are provided vertical water conduits and horizontal air conduits.

In all radiator structures it is the aim of the manufacturer to produce a radiator which may be manufactured and sold at a reasonable figure as well as being highly efficient for its size, measured in area and depth. It has been the tendency for radiator manufacturers, in order to increase the efficiency of the radiator without increasing the size thereof, to provide multiple indentations or protrusions in the walls of both the water and air conduits. It is believed the point has been reached wherein increased cooling cannot be obtained by increasing the number of indentures or protrusions in the various passages. Improvement in cooling capacity must therefore be directed along the lines of simplifying rather than complicating the construction of a core and it is along this latter line that applicant has developed a radiator construction of which the following specification is a full and complete description.

The principal object of this invention is to produce a radiator, the air and water passages of which are formed to obtain maximum cooling from a minimum sized core.

Another object of this invention is to provide a radiator having water passage strips, the exterior surfaces of which co-operate with the separator strips to deflect the air passing through said air passages and increase the cooling efficiency.

A further object of this invention lies in the provision of water and air conduit strips, the construction of which is such that the manufacture and assembly thereof is greatly simplified and consequently less costly.

Other and further objects of this invention will appear from a consideration of the following specification when taken in conjunction with the accompanying drawings which forms a part thereof; and in which

Fig. 1 is a front elevation of a radiator embodying one form of this invention;

Fig. 2 is a perspective view of one of the water conduit strips showing the protrusions formed thereon;

Fig. 3 is an enlarged fragmentary perspective view of one of the separator strips;

Fig. 4 is a horizontal sectional view of the water passage strip taken substantially on the line 4-4 of Figure 2;

Fig. 5 is a horizontal sectional view of the separator strip taken substantially on the line 5-5 of Figure 3; and

Fig. 6 is a fragmentary vertical sectional view of a portion of the assembled core.

It is well known that the rate of heat exchange is higher when the flow of the cooling medium is turbulent than when it is more or less tranquil or in stream-line. This applies particularly in the use of water, air or similar media for cooling purposes. However, it is not sufficient that the flow of the cooling medium be made turbulent, but that it be dynamically balanced so that the energy consumed in breaking up the flow of this medium into eddies and thus causing sufficient turbulence shall be less than the gain in heat exchange. This is best illustrated in a radiator having small mouthed air passages. The air being greatly restricted it is true, sets up a violent turbulence and thus perforce increases the heat exchange to a certain extent, but the amount of power or energy required to force the air through the restricted openings becomes so great that the slight increase in heat exchange attained is over-balanced. A further consideration lies in the fact that a balance between the thermal and dynamic characteristics of the air passages must be maintained. This is particularly true in the present structure where in certain of the wall strips are in direct contact with the water to be cooled and therefore their temperature is higher than that of the separator or spacing strips which derive their heat therefrom.

From the foregoing it will be understood that it is essential to provide efficient dynamic balance between the air and water conduits so as to produce eddies and turbulence

without unduly interfering with the flow of either air or water, and it is also essential that the velocity distribution and the temperature distribution in the air passages shall be such that the heat exchange capacity per unit surface shall attain a maximum value.

In order to obtain these results the wall strips forming the water conduits and the separator or spacing strips are provided with indentures or projections of such dimensions that they are easily impressed in the strips and form integral parts thereof.

Referring to the drawings, the reference numeral 10 is employed to designate a radiator assembly, such assembly comprising in general a shell 12 and a core 13. Upper and lower water tanks (not shown) are provided, the upper tank supplying water to the core 13 and the lower tank carrying the cooled water away. Vertical water conduits 15 connect the upper and lower tanks. Horizontal air conduits 16, 17 and 18 are formed between the water passages 15 for the purpose of cooling the water within said passages. The water conduits are formed by a series of thin metal strips 20 which also act to form one wall of the horizontal air conduits. Referring to Figure 6 of the drawings, it will be noted that the water conduits 15 are formed by the strips 20 ranged in pairs and immediately contacting within the outer face of the wall strips are separator or spacer strips 21 which constitute the other walls of the air conduits 16, 17 and 18.

The structure and operation of a radiator of the embodiment shown are old and well known and need not be described in detail. It may be briefly stated, however, that the water to be cooled enters the upper tank, flows through the conduits 15 into the lower tank from which it is returned to the engine. The flow of water from the upper to the lower tank and through the conduits 15 is in the form of a thin film or sheet and the air passing through the air conduits 16, 17 and 18, usually under the influence of a fan, acts upon the wall strips 20 extracting heat therefrom, thereby lowering the temperature of the water as it passes downwardly through the conduits 15.

The strip 20, two of which form each water conduit 15, is shaped to provide longitudinal margins 23. Slightly raised from the margins 23 by the sloped wall 24 is a flat surface 26, provided with horizontal uniformly spaced ribs 28 which extend from one sloped wall to the other. Since the ribs 28 are spaced apart, a flat portion 29 is formed between each pair thereof. The strip 20 terminates top and bottom in flanges 30 by means of which the outer wall of one water conduit is joined to the intermediate or separator strip and the wall of the next adjoining water conduit. When a pair of the wall strips are placed together, with the ribs 28 projecting

outwardly from each other, and the margins 23 contacting, the vertical passageway or conduit 15 is formed. It will be understood that, although the conduit 15, by reason of the flat portions 29, is a substantially vertical 70 passageway, water passing through said conduit in a thin stream will adhere to the wall strips 20 following the depressions created on the inner face of each of the ribs 28.

The separator strip 21, shown in Figures 75 3 and 5 of the drawings, is of zigzag conformation. This strip may, for the purpose of description, be considered to be divided into parts 32 and 33. While these parts are integral, they are oppositely shaped and are 80 the equivalent of two separate and oppositely faced strips. The part 32, along its margin 35, is provided with large bends or angles 36 and 37, the alternate angles of which extend in the same direction. The bend or angle 36, 85 adjacent the margin 35, is formed with a shallow or small reverse bend 38. The depression created by the bend 38 is of a magnitude equal to that of the ribs 28 formed in the strip 20 and is for the purpose of engaging 90 and positioning said strip during assembly. The end 38 extends slightly more than half the width of the strip 21 and terminates abruptly in a cut edge 39. The bend or angle 37, which is opposite to the bend 36, is formed 95 adjacent the margin 35 with a small reverse bend 41. This bend is likewise of the same magnitude of the rib 28 and is for the purpose of engaging one of said ribs at the time of assembly. Attention is directed to the 100 fact that the reverse bend 41 is shorter than the bend 38 and that it fails to reach the center of the strip 21 by approximately the same distance that the reverse bend 38 passes the center of said strip. This bend is terminated 105 by a cut edge 42 which separates it from the horizontally adjoining portion of the strip. The edges 39 and 42 may therefore be considered to be vertically staggered.

Referring now to the part 33 of the strip 110 21, it will be noted that large bends or angles 44 and 45 are formed in the marginal portion 46. The bend 45 projects in the opposite direction from the bend 36 with which it is in horizontal alignment. Adjacent the margin 46, in the bend 45, a small reverse bend 48 is formed, which reverse bend extends to the cut edge 39 of the reverse bend 38. As above stated, the bend 38 extends slightly beyond the center of the strip and therefore the bend 48 fails to reach the center. It is to be understood that the bend 48 corresponds in direction and length to the bend 41 of the part 32. The large bend 44, adjacent the margin 46, is formed with a reverse bend 50, the length of which passes the center of the strip and terminates in the edge 51 which is adjacent the edge 42 of the reverse bend 41. It will be noted that the bend 50 extends in the same direction and is of the same length 115 120 125 130 135

as the bend 38. By reason of the above description, it will be understood that the large bends 37 and 44 extend in opposite horizontal directions and that the alternate bends, formed in each part of the strip, project in the same direction, for example, the bends 37, 45 and 36, 44. It will be further noted that the small reverse bends 38 and 41 are staggeredly arranged with the small reverse bends 48 and 50. As for example, the short reverse bend 41, formed in the part 32, is one bend removed from the short reverse bend 48 formed in the part 33 and further that the long reverse bend 38, formed in the part 32, is one bend removed from the long reverse bend 50 of the part 33. Where the short bend of one part approaches the long bend of the adjacent part an opening 53 is formed. By reason of this opening, air passing along the surface of the bend 41 upon one face of the strip will pass through the opening 53 and along the bend 50 on the other face of the strip. Each current of air therefore is directed to both faces of the separator strip by passing through the opening 53 from one face to the other. Due to the staggered arrangement of the reverse bends, the openings 53 are likewise staggered.

In assembling a radiator of this type two of the strips 20 are placed together, margin to margin, and with the ribs 28 projecting outwardly to form the water conduit 15. The separator strip 21 is brought into position against the outer face of the strip 20 and the ribs 28 engage the reverse bend portions of the said strip. For example, by placing the strip 21 shown in Figure 3 against the strip 20 in Figure 2, the uppermost rib 28 will be engaged through a portion of its length by the bend 41. The second rib through a portion of its length will be engaged by the reverse bend 48, etc. Since there is but one separator strip, between each water conduit, the next adjoining water conduit, comprised of two strips 20, is placed against the other face of the separator strip 21, etc., until the core is completed.

Referring now to Figure 6 of the drawings, it will be noted that, when the core is completely assembled, the water conduits 15 form vertical passages through which the water may freely flow without danger of clogging. Normally with but one separator strip between each water conduit only two air passages are formed. However, and by reason of the fact that the separator strip 21 is formed in vertically and oppositely arranged parts 32 and 33, a separator strip, when placed between two water conduits, forms the three air passages referred to above. By reason of this structure it is possible to break up the flow of air passing through said air passages without greatly restricting it and setting up any reverse currents, by which to decrease the cooling capac-

ity of the air. In other words, the air currents although being minutely broken up have not been retarded to any appreciable extent in their passage through the core to decrease the efficiency of the heat exchange as between the cooled air and the heated walls of the passages.

While applicant has shown and described but one modification of this invention, he does not intend to be limited thereto since it is obvious that other modifications or adaptations may be made without departing from the spirit and scope of this invention other than as set forth in the hereunto annexed claims.

Having thus set forth my invention what I claim as new and for which I desire protection by Letters Patent is:

1. A radiator including in combination a plurality of metal strips forming vertical water and horizontal air conduits, vertical marginal portions defining the edges of said water conduit strips, marginally limited horizontal means formed integral with and extending outwardly from the walls of said water conduit strips, said air conduit strip being of zigzag conformation, the bends of said zigzag abutting the margins of adjacent water conduit strips, and means formed in horizontally aligned bends adapted to engage the horizontal means of the adjacent water conduit strips.

2. A radiator comprising a series of wall strips, two of which form a water passage, and a series of division or separator strips, one of which is mounted between and spaces adjacent water passages, horizontally disposed ribs formed integral with said wall strips, horizontally disposed means formed in said separator strip, said means, when said radiator is assembled, being in engagement with a portion of the horizontally aligned rib in the wall strip of one water passage and also with a portion of the horizontally aligned rib in the wall strip of the adjacent water passage and further means in said separator strip causing air passing through said radiator to move from one air passage to another.

3. In a radiator, a series of wall strips forming vertical water conduits, a series of separator strips forming with said wall strips horizontal air conduits, marginally limited horizontal protrusions in said wall strips and staggeredly arranged depressions and projections in said separator strip, one of each of said depressions and projections being arranged in the same horizontal plane whereby said projection will engage the wall strip of one water passage and said depression will engage a corresponding portion in the wall strip of the next adjacent water passage.

4. In a radiator, a series of wall strips forming vertical water conduits, a series of separator strips forming with said wall strips horizontal air conduits, each of said sepa-

rator strips being vertically divided into reversely disposed parts, bends defining the margins of said separator strip, the bends of one margin being reversely disposed with relation to the bends of the other margin, and means adjacent the vertical center of said separator strip defining said vertical parts, said means causing the flow of air to pass part way through said radiator along one face 10 of said separator strip and emerge from said radiator along the opposite face of said separator strip.

5. A radiator including in combination a plurality of metal strips forming straight 15 vertical water and horizontal air conduits, vertical marginal portions defining the edges of said water conduit strips, marginally limited horizontal ribs formed integral with and extending outwardly from the walls of 20 said water conduit strips, said air conduit strips being longitudinally divided into reversely disposed parts, bends defining the margins of said air conduit strip, the bends of one margin being reversely disposed with 25 the corresponding bends of the other margin of said strip and means adjacent the center of said air conduit strip defining vertically divided parts, said means causing the flow of air to enter said radiator between one 30 face of said air conduit strip and said water conduit and emerge from said radiator along the opposite face of said air conduit strip.

6. A radiator having a plurality of water and air conduits, a pair of metal strips forming one of said water conduits, straight marginal portions defining the vertical edges of each of said strips, said strips, when assembled, being arranged with adjacent marginal portions in contact, transversely disposed 40 angular ribs extending from margin to margin, the ribs on opposing strips being arranged opposite to each other and directed outwardly so as to form enlarged water chambers connected with the vertical water 45 passage between said strips defined by the portion of each strip between said ribs and within the marginal portions, and a separator strip mounted between adjacent water conduits, said strip being engaged with each 50 of said outwardly directed ribs in the adjacent walls of adjacent water conduits.

7. In a radiator having a plurality of water and air conduits, a pair of metal strips having full length depressions therein which 55 form, when reversely engaged, straight water conduits, a separator strip mounted between adjacent walls of adjacent water conduits, zigzag portions in said strips, said strip being vertically cut, with the portions each 60 side of said cut projecting in opposite directions whereby said separator strip is made to engage horizontally opposite projections in adjacent walls of adjacent water conduits.

8. A radiator including in combination a 65 plurality of metal strips forming vertical

water and horizontal air conduits, vertical marginal portions defining the edges of said water conduit strips, marginally limited means projecting outwardly from the walls of said water conduit, a separator strip interposed between adjacent wall strips and being formed in zigzag bends, reversely disposed means in each of said bends adapted to engage the horizontally opposite outwardly extending means in adjacent wall strips of adjacent water conduits. 75

9. In a radiator having a plurality of water and air conduits, a separator strip, zigzag angular bends defining the margins of said strip, the angular bend of one margin being reversely disposed to the corresponding angular bend of the other of said margins whereby to provide irregularly disposed contact of said separator strip with the adjacent water conduits. 85

In testimony whereof I have affixed my signature.

OTTO CARLSON.
